W. S. SHERLOCK.
AUTOMOBILE LAMP.
APPLICATION FILED MAR. 21, 1916.

Patented Sept. 5, 1916.

FIG. 3.

FIG. 4.

INVENTOR
William S. Harbeck.
by
Oscar Oscar Englehardt.

UNITED STATES PATENT OFFICE.

WILLIAM S. SHERLOCK, OF TOLEDO, OHIO, ASSIGNOR OF ONE-FOURTH TO ARCHEBOLD W. GRIFFIN, ONE-FOURTH TO WILLIAM C. SCHOEDLER, AND ONE-FOURTH TO CLYDE R. FISHER, ALL OF TOLEDO, OHIO.

AUTOMOBILE-LAMP.

1,197,237.

Specification of Letters Patent.

Patented Sept. 5, 1916.

Application filed March 21, 1916. Serial No. 85,601.

To all whom it may concern:

Be it known that I, WILLIAM S. SHERLOCK, a citizen of the United States, and a resident of Toledo, in the county of Lucas and State of Ohio, have invented a certain new and useful Automobile-Lamp; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to lamps.

It particularly relates to means for deflecting or directing at will the rays of light projected from an automobile lamp at an angle to the axis of the lamp.

20 It has for its object to direct the projected rays from the lamp, or a part of them, downward to prevent the blinding glare which often causes serious accidents in connection with automobiles, cars, etc. The 25 construction, however, may be used for deflecting the rays of light sideways for the purpose of causing the rays of light to light the way when the automobile is to be turned.

30 The invention may be contained in many forms of constructions usable for different purposes, all of which come within the purview of my claims hereinafter appended. To show the practicability of my invention 35 I have selected one of such constructions as an example and shall describe it herein-after. The construction selected is illustrated in the accompanying drawings.

Figure 1 of the drawing is a sectional view of a construction containing my invention. Fig. 2 is a rear view of the lamp as showing the housing for the solenoid which operates the reflector. Fig. 3 is a modification of the invention illustrated in 45 Fig. 1. Fig. 4 is a system illustrating diagrammatically the connections that may be used in connection with the lamp.

50 1, Fig. 1, is the outer shell of the lamp, while 2 is a rim containing the glass disk or prism 3. The shell 1, the rim 2 and the prism 3 inclose the reflector and the other parts of the construction.

55 4 is a reflector. It is formed of two parts, 5 and 6, the edges of which abut and make

a complete reflector substantially parabolic 55 in form. The abutting edges of the parts 5 and 6 are located on a plane at an angle to the axis of the lamp. They are hinged together at their upper edges by the hinge 7. This arrangement places the center of 60 gravity of the part 6 well outside the vertical line passing through the hinge 7 and thus causes the part 6 to readily close by its own weight.

The lamp 10 is set into a socket 11 which 65 is located in the axis of the reflector 4. Wires 12 and 13 connect the lamp 10 with a source of current supply such as a storage battery. A bracket 15 is secured near the lower edge of the part 6 of the reflector 4. 70 A movable core 16 of a solenoid 17 is connected by means of a link 18 and a spring pressed latch lever 25 to the bracket 15. The solenoid 17 is contained in a housing 19 which is struck up from the body portion 75 of the shell 1. The solenoid 17 is secured to the rear wall 20 of the housing 19. An underplate 21 closes the housing 19. The plate 21 may be secured by screws 22 and 23. The plate 21 may thus be easily removed whereby access to the solenoid and its connecting parts is easily obtained.

The engaging latch lever or hook 25 engages with the projection 26 located on the part 5 of the reflector 4. A spring 27 operates upon the latch lever 25 to press the latch lever so that it will be held in engagement with the projection 26. The core 16 is connected with the lever 25 so that when the core is drawn into the solenoid 17 it 80 will move the lever 25 about its pivot and cause disengagement with the projection 26. Upon further movement of the core 16 the part 6 of the reflector 4 will be swung back to the dotted position indicated in the figure. When this occurs the rays of light which are reflected by the portion 6 of the reflector 4, that is, the more concentrated rays, will be tilted down from the axis of the lamp, causing the more intense reflected light to be directed toward the road, also the lamp will be turned out of the axis of the remainder or main portion of the reflector. This prevents the rays of the lamp from blinding the eyes of a person looking 100 toward the lamp. The solenoid 17 is connected by wires 30 and 31 which may be connected to a suitable source of supply,

such as the storage battery of an automobile.

In the modification shown in Fig. 3 the part 35 of the reflector 36 is pivoted to the part 37 by pivot pins which extend through ears 38 and 39 and which are located in a line passing through and at right angles to the axis of the lamp. If it is desired to tilt the more concentrated rays of the light 10 down the pivot pins are located in a horizontal line passing at right angles to and through the axis of the lamp. The edges of the parts 35 and 37 are located in a plane at right angles to the axis of the lamp. By 15 this arrangement the upper edge of the part 35 passes within the part 37 of the reflector 36 while the lower edge of the part 35 swings away from the edge of the part 37 when the part 35 is tilted. The lamp 10 20 is secured in the axis of the reflector 36. It is secured to the part 35 and in the socket 11. Also, the part 35 may be tilted by a solenoid. A solenoid 45 is supported in a housing 46 which is closed by a plate 47. 25 A bracket 48 is secured to the lower edge of the part 35 and is connected to the core 49 by means of a link 50. A bracket 51 is secured to the edge of the part 37 of the reflector 36. The two brackets 48 and 51 are 30 connected together by a spring 52. They are also provided with abutting parts 53 which abut when the core 49 is released by the solenoid 45 and the spring 52 draws the lower edge of the part 35 to the part 37. 35 The solenoid 17 or 45 may be controlled by switches of any form. In Fig. 4 I have shown conventionally a system for operating the lamp. 60 is a storage battery which is connected by a line 12 to the lamp. The 40 line 13, also connected to the lamp, is connected to the switch 61, which, when closed, will cause the lamp to be lighted by the storage battery, the circuit being completed by the line 62. The solenoid 17 is connected 45 by the wire 30 to the line 12, and through the line 12 to the storage battery 60. The other terminal of the solenoid 17 is connected by the wire 31 to the switch 63, which also completes a circuit to the storage battery 50 through the wire 62. When the switch 63 is closed the solenoid will cause the more intense or concentrated rays of light to be

deflected from the axis of the lamp. A push button 65 may also be connected in shunt with the switch 63, for causing the solenoid 17 to operate momentarily.

The construction selected and described may be greatly modified in the arrangement and manufacture of its parts and in the substitution of elements having equivalent 60 functions, and such modifications may be used for many varied purposes and still contain the invention.

Having thus described my invention, what I claim as new and desire to secure 65 by Letters Patent, is,—

1. In a lamp, the combination of a shell, a parabolic reflector located within the shell and formed of two parts, the edges of the two parts located in a plane at an angle to the axis of the reflector, a hinge, the two parts hinged together at a point in the edges of the two parts located nearest the edge of the reflector, a latch for locking the two parts together, and an electromagnetic 75 means connected to the latch for opening the latch and moving the central part of the reflector about the hinge.

2. In a lamp, the combination of a shell, a parabolic reflector located within the shell 80 and formed of two parts, the edges of the two parts located in a plane at an angle to the axis of the reflector, a hinge, the two parts hinged together at a point in the edges of the two parts located nearest the edge of 85 the reflector, a latch for locking the two parts together, an electromagnetic means connected to the latch for opening the latch and moving the central part of the reflector about the hinge, a housing extending rearwardly from the shell, and a removable plate located on the lower side of the housing for closing the housing.

3. In a lamp, the combination of a shell, a two-part reflector located within the shell, 95 means for supporting one of the parts for rotative movements relative to the other part, a latch for locking the two parts together, and a means connected to the latch for opening the latch and rotatively moving 100 one part of the reflector.

In testimony whereof, I have hereunto signed my name to this specification.

WILLIAM S. SHERLOCK.
